BRANDING IRON

Raphael Lyman, Nursery St., Norwalk, Conn.

Filed Dec. 27, 1962, Ser. No. 72,969

Term of patent 14 years

(Cl. D81—10)

FIG. 1 is an elevational view of one side of a branding iron, showing my new design;

FIG. 2 is an end view of the same;

FIG. 3 is a fragmentary, elevational view of the same taken at an angle of approximately 110° to that of FIG. 1;

FIG. 4 is a view similar to that of FIG. 3 rotated in a direction opposite to that of FIG. 3;

FIG. 5 is a fragmentary view similar to that of FIG. 1, rotated at an angle of 180° relative thereto.

The article is shown broken away in FIG. 1 to indicate indeterminate length. The handle portion shown in FIG. 1 is cylindrical throughout its cross-section.

I claim:

The ornamental design for a branding iron, substantially as shown and described.
